Filed Jan. 21, 1969, Ser. No. 15,434

Term of patent 14 years

Int. Cl. D23—04
U.S. Cl. D23—146

FIG. 1 is a front perspective view of a humidifier or the like embodying our new design;

FIG. 2 is a top plan view thereof;

FIG. 3 is a side elevational view thereof, the other side being identical; and

FIG. 4 is a bottom plan view thereof.

The mesh-like pattern is partially shown on the humidifier cap for convenience of illustration and is understood to be continuous over said area as indicated by the conventional cross-hatching.

We claim:

The ornamental design for a humidifier or the like, as shown and described.
